UNITED STATES PATENT OFFICE

144,108

DESIGN FOR A TORPEDO DIRECTOR

Robert M. Freeman, United States Navy, assignor to the Government of the United States of America, as represented by the Secretary of the Navy

Application January 5, 1944, Serial No. 112,173

Term of patent 3½ years

(Cl. D52—1)

To all whom it may concern:

Be it known that I, Robert M. Freeman, a citizen of the United States and an officer in the United States Navy, have invented a new, original, and ornamental Design for a Torpedo Director, of which the following is a specification, reference being had to the accompanying drawing, forming part thereof.

The essential features of my design reside in the portions shown by means of full lines in the drawing.

I claim:

The ornamental design for a torpedo director, as shown and described.

ROBERT M. FREEMAN.
